UNITED STATES PATENT OFFICE.

JOHN JACOB FURTHMILLER, OF GRAETTINGER, IOWA.

HARROW.

SPECIFICATION forming part of Letters Patent No. 711,956, dated October 28, 1902.

Application filed March 15, 1902. Serial No. 98,363. (No model.)

To all whom it may concern:

Be it known that I, JOHN JACOB FURTHMILLER, a citizen of the United States, residing at Graettinger, in the county of Palo Alto 5 and State of Iowa, have invented a new and useful Harrow, of which the following is a specification.

This invention relates generally to harrows and more particularly to certain attachments 10 applicable to drag-harrows, whereby the toothed bars can be held at any desired angle; and another object of the invention is to provide a construction whereby one or more of the toothed bars can spring back in case an 15 obstruction is met with, thereby avoiding the breaking of the harrow tooth or bar.

With these objects in view the invention consists in the novel features of construction and combination, all of which will be fully 20 described hereinafter and pointed out in the claims.

In the drawings forming part of this specification, Figure 1 is a perspective view illustrating my invention. Fig. 2 is a vertical 25 longitudinal section. Fig. 3 is a detail transverse section. Fig. 4 is a modified form of spring employed for connecting toothed bar-arms to the central beam.

In carrying out my invention I employ side 30 beams A, a central beam B, and journaled in said central and side beams are the horizontal toothed bars C, said bars having upright arms D rigidly connected thereto adjacent to the central beam B, and directly 35 above the central beam B is a supplemental central beam E, having a series of stop-plates E' attached thereto and against which the upright arms D are adapted to rest when the harrow-teeth F, carried by the bars C, are in 40 vertical position, and in order to normally hold the teeth in such position I employ the coil-springs G, one end of each spring being connected to the bar E, while the opposite end is connected to the adjacent upright D, 45 the tension of the spring holding the arm against the stop E'. The bar E is supported upon arms E², and a lever H, pivotally connected at its lower end to one of the toothed bars, is pivotally connected adjacent to its

lower end to the bar E and is provided with 50 a thumb-latch H', the pawl of which is adapted to engage the toothed segment H², carried upon the bar E, and by throwing the lever back or forth the bar can be shifted, and when the bar is shifted the inclination of the 55 harrow-teeth will also be shifted, inasmuch as the springs normally hold the upright arms against the angular stops. In case one or more harrow-teeth should meet with an 60 obstruction the spring connected to the upright arm will yield, permitting the tooth to spring rearwardly, as most clearly illustrated in Fig. 2, and in this manner all danger of breaking the toothed bars is avoided.

Various forms of springs may be employed; 65 and in Fig. 4 I have illustrated several different modifications, it being apparent that any suitable form of spring may be employed which will normally hold the upright arms against angular stops. 70

Having thus fully described my invention, what I claim as new, and desire to secure by Letters Patent, is—

1. A harrow comprising the longitudinal beams, the transverse toothed bars, each having an upright arm attached thereto, a longitudinally-movable shifting bar having stops arranged thereon, the upright arms attached to each toothed bar, and adapted to normally rest against the stops upon the shifting bar, 75 means for holding the said arms against the stops, and means for operating the bar, substantially as described.

2. A harrow comprising the longitudinal beams, the transverse toothed bars journaled 85 in the beams, and carrying harrow-teeth, each toothed bar having an upright bar connected thereto adjacent to the center, a longitudinal shifting bar having laterally-projecting stops adapted to engage the upright arms the 90 springs connecting the shifting bar and the upright arms, and a lever for operating the shifting bar, substantially as described.

JOHN JACOB FURTHMILLER.
